CABINET

Elizabeth D. Hartzell, 417 W. Barry Ave., Chicago, Ill.

Filed Jan. 11, 1965, Ser. No. 83,388

Term of patent 14 years

(Cl. D33—19)

FIGURE 1 is a perspective view of a cabinet showing my new design, the cabinet being shown in its opened position;

FIG. 2 is a perspective view of the same showing the cabinet in closed position;

FIG. 3 is a side view of the same showing the cabinet in closed position; and

FIG. 4 is a sectional view of the same as taken on the plane of line 4—4 of FIG. 2 to show the interfitted relation of the front panel of the cabinet when in closed position.

The side of the cabinet not shown is like the side shown while the top and back are plain and unornamented.

The dominant features of my design reside in those portions shown in full lines in the drawing.

This application is a continuation-in-part of my co-pending application Serial No. D. 73,431, filed February 4, 1963, and now abandoned.

I claim:

The ornamental design for a cabinet, as shown and described.
